UNITED STATES PATENT OFFICE.

PETER S. ROLLER, OF MOUNT JACKSON, VIRGINIA.

TRACK-GAGE.

Patented July 6, 1909.

No. 926,770.

Specification of Letters Patent.

Application filed September 18, 1908. Serial No. 453,590.

To all whom it may concern:

Be it known that I, PETER S. ROLLER, citizen of the United States, residing at Mount Jackson, in the county of Shenandoah and State of Virginia, have invented certain new and useful Improvements in Track-Gages, of which the following is a specification.

This invention comprehends certain new and useful improvements in gages and relates particularly to an improved construction of track gage combining in the one instrument all of the functions of a gage and leveling board, doing away with the necessity for a separate instrument for use in leveling the track, the present device being designed primarily for determining the proper elevation of the outside rail on curves of different degrees, as well as in determining whether or not the two rails are the proper distance apart.

For a full understanding of the invention, reference is to be had to the following description and accompanying drawings in which:

Figure 1 is a side elevation of my improved track gage illustrating one application thereof; Fig. 2 is a similar view illustrating another application; Fig. 3 is a top plan view of the yoke; Fig. 4 is a transverse sectional view through the arm of the device; Fig. 5 is a similar view through the straight edge illustrating the spirit level secured thereto; and, Fig. 6 is a detail sectional view illustrating the adjustable connection between the straight edge and the scale bar.

Corresponding and like parts are referred to in the following description and indicated in all the views of the accompanying drawings by the same reference characters.

My improved track gage comprises an arm 1 which is provided at one end with a depending lug 2 forming an outwardly facing shoulder designed to engage the inner edge 45 of the tread surface of the outside rail of a railroad track, said arm being provided at its opposite end with a yoke 3 the members of which are correspondingly provided with lugs 4 designed to engage the inner edge of 50 the tread surface of the inner rail. The arm 1 is formed in one side with a longitudinally extending and upwardly facing recess 5 in which a straight edge 6 is pivoted at one end, the straight edge being pivotally connected 55 to the arm at the outer end of the latter, the position of the device during operation being

considered. The free end of the straight edge 6 carries a clamping bolt 7 with a set screw mounted thereon, the said clamping bolt being designed to engage a scale bar 80 which is pivotally connected at one end to the arm 1 where the arm joins the yoke 3; the said scale bar being designed to swing in a vertical plane, and being arranged, when not desired for use, to be swung downwardly 65 in a pocket 9 formed in the arm 1 so that it will then be entirely out of the way. The yoke 3 is formed with a recess 10 designed to receive the set screw of the clamping bolt 7 when the straight edge 6 is swung downwardly to an inoperative position, it being particularly noted that when the straight edge and scale bar are not in use and are held in their inoperative positions relative to the arm and yoke, there will be no projecting 75 parts whatever to interfere with the use of the device as a simple track gage.

11 designates a spirit level which is provided on one side with nibs 12 designed to engage the straight edge 6 as clearly illustrated in Fig. 5, a clamping screw 13 being mounted on an extension or bracket of the case of the spirit level and designed to impinge against the straight edge so as to securely hold the spirit level thereon; preferably the straight edge is formed with a slight indentation 14 in which the clamping screw 13 works.

In the practical use of my improved track gage, it is to be understood that the scale bar 90 8 contains graduations in degrees and minutes which are laid off thereon according to the accepted formulae that may be worked out according to the radius of a curve, the gage of the track, and the velocity of a car 95 per minute in determining the proper elevation of the outer rail at the curve. With this understanding, it will be seen that when the gage is applied to a track at a curve with the yoke 3 engaging the inner rail, the proper 100 elevation of the outer rail may be at once easily determined by raising the free end of the straight edge until it engages the upwardly extending scale bar at the proper graduation according to the degree of the 105 curve; then when the spirit level is secured to the straight edge, the outer rail is raised until the straight edge assumes a true level position which will determine the proper elevation of the outer rail. When the device 110 is used on straight stretches of track, the straight edge and scale bar are swung to an

2

inoperative position and the spirit level may rest loosely upon the upper edge of the arm 1 to determine whether or not the two rails are level or whether one or the other needs to be 5 raised.

From the foregoing description, in connection with the accompanying drawings, it will be seen that I have provided a very simple, durable and efficient construction of 10 track gage and leveling device combined, which embodies comparatively few parts that may be easily manufactured and readily assembled and which may be used by any ordinary track man without any special 15 knowledge of mechanics.

Having thus described the invention, what is claimed as new is:—

1. A track gage comprising an arm provided with a longitudinally extending recess, 20 a straight edge pivotally connected thereto and movable in a vertical plane and arranged to be accommodated in said recess, the arm being formed at the inner side of said straight edge with a pocket, a scale bar pivotally connected at one end to the arm to move about a horizontal axis and designed to be accommodated in said pocket, a clamping bolt carried by the free end of said straight edge and arranged to connect the same to the scale bar, 25 and a spirit level carried by said straight edge.

2. A track gage comprising an arm, a

to me formed at with a pocket to the arm to move and designed to be a pocket, means for connecting one end edge to the scale bar, and a spirit level carried by the straight edge.

3. A device of the character described, comprising an arm, provided with a longitudinally extending recess, a straight edge pivotally connected to the arm to move in a vertical plane and arranged to be accommodated in said recess, the arm being formed at the inner side of said straight edge with a pocket, a scale bar pivotally connected at one end to the arm to move about a horizontal axis and designed to be accommodated in said pocket, a clamping bolt carried by the free end of said straight edge and arranged to connect the same to the scale bar, the bolt being provided with a set screw, and a spirit level designed for removable connection to the straight edge.

In testimony whereof I affix my signature in presence of two witnesses.
